Patented Sept. 23, 1975

236,896

DRY CLOSET

Peter Nordgren, Gustavberg, Sweden, assignor to AB
Gustavsbergs Fabriker, Gustavberg, Sweden

Filed Aug. 8, 1974, Ser. No. 495,879

Claims priority, application Sweden Feb. 19, 1974

Term of patent 14 years

Int. Cl. D23—02

U.S. Cl. D23—48

FIG. 1 is a front perspective view of a dry closet showing my new design; and

FIG. 2 is a rear perspective view thereof.

I claim:

The ornamental design for a dry closet, as shown.
